UNITED STATES PATENT OFFICE.

THEODORE BIRKENMAIER, OF ST. LOUIS, MISSOURI.

STENCIL-CUTTING MACHINE.

1,149,151.

Specification of Letters Patent.

Patented Aug. 3, 1915.

Application filed May 5, 1913. Serial No. 765,711.

To all whom it may concern:

Be it known that I, THEODORE BIRKENMAIER, a citizen of the United States, and residing at St. Louis, in the State of Missouri, have invented certain new and useful Improvements in Stencil-Cutting Machines, of which the following is a specification.

This invention relates to stencil cutting machines and one of its objects is to construct a machine in which the blank will be exposed to view at the cutting point, whereby the work of the machine is visible.

Another object is to construct a stencil cutting machine in which the punches and dies are adapted to operate on a blank positioned at an angle to the horizontal, and to provide means for supporting and feeding the blank in such a position with respect to the punches and dies.

Another object is to construct a stencil cutting machine in which the blank will not only be visible at the cutting point but in which each stencil line after being cut is fully exposed to view so as to be in plain view before the operator.

Another object is to provide improved blank supporting and feeding means which is constructed and arranged to accurately and positively feed the blank.

Further objects will appear from the detail description taken in connection with the accompanying drawings, in which:

Figure 1 is a plan view of a machine showing one embodiment of this invention, Fig. 2 is a side elevation, Fig. 3 is a section on the line 3—3 Fig. 1. Fig. 4 is a side elevation of the blank carriage. Fig. 5 is a section on the lines 5—5 Figs. 3 and 6 showing the mechanism for feeding the carriage laterally, Fig. 6 is a side elevation of Fig. 5, parts being shown in section, Fig. 7 is a detail side elevation showing the mechanism for feeding the blank carriage vertically, Fig. 8 is a detail section through the blank carriage shaft and hub, showing the means for latching the carriage in its different adjusted positions, Fig. 9 is a detail vertical section through the rim of the carriage, Fig. 10 is a face view and Fig.

11 is a section on the line 11—11 Fig. 10, showing the punch partly formed, Fig. 12 is a face view and Fig. 13 is a section on the line 13—13 Fig. 12, showing the punch fully formed, Fig. 14 is a face view and Fig. 15 is a section on the line 15—15 Fig. 14, show-

ing the die plate partly formed, Fig. 16 is a face view and Fig. 17 is a section on the line 17—17 Fig. 16, showing the die plate fully formed, Fig. 18 is a detail section showing the stripper, Fig. 19 is a detail plan view of the stripper, Fig. 20 is a plan view illustrating another embodiment of this invention, Fig. 21 is a front elevation, Fig. 22 is a detail plan view, Fig. 23 is a section on the line 23—23 Fig. 23, Fig. 24 is a detail front elevation showing the operating handle and its connections, Fig. 25 is a section on the line 25, Fig. 26 is a side elevation partly in section of Fig. 25, Fig. 27 is a detail section through the carriage, Fig. 28 is a section on the line 28 Fig. 27, Fig. 29 is a side elevation of the machine of Figs. 1 to 19 inclusive, showing an attachment for cutting a circular stencil, Fig. 30 is a front elevation of the attachment, Fig. 31 is a section on the line 31—31 Fig. 29, Fig. 32 is a side elevation showing a circular stencil cutting attachment for the machine shown in Figs. 20 to 28 inclusive, Fig. 33 is a rear elevation of the attachment, and Fig. 34 is a section on the line 34—34 Fig. 33.

Referring to the accompanying drawings, 10 designates a base adapted to support the punch and die carrier. This punch and die carrier is of cylindrical construction and may either be formed integral, or may be formed of two pieces secured together so as to form in effect a single element. As shown in the drawings the die carrier 11 and the punch carrier 12 are secured together by screws 13. The punch and die carriers are separated by an annular space 14 adapted to receive the blank carriage hereinafter to be described, and are supported on the base 10 by means of balls 15. A ring 19 clamped to the base and taking over an inwardly projecting flange 20 serves to retain the punch and die carrier in position. The punch and die carrier is provided with a hand wheel or rim 21, preferably cast integral with the carrier.

The upper end of the carrier 11 has a machined face to receive a series of die plates 25 secured to the carrier by means of screws 105 26 in a manner well known to those skilled in the art. These die plates are formed with the usual stencil-characters and the die carrier is recessed as shown at 27 to permit the punchings to drop out. A series of plungers 110

28 are mounted in bearings in the spaced annular lugs 29 and 30 on the punch carrier. These plungers support the punches 31 which are preferably separate plates secured to the plungers. The plungers 28 are moved inwardly toward the center of the machine by means of springs 32 bearing against the yokes 33 secured to the plungers by screws 34 and embracing pins 35 mounted in the lugs 29 and 30. The punches 31 and dies 25 may be of any suitable construction but are preferably constructed and formed in a manner hereinafter to be described.

15 A bracket 40 integral with the base 10 is provided at its upper end with a radially extending bearing for an operating plunger or ram 41 having a hooked end adapted to coöperate with the hooked ends 42 of the plungers 28. This bracket is further provided with a radially extending bearing for a centering pin 43 adapted to enter flared holes 44 in the punch carrier 11, there being a flared hole below each punch. A lever 45 is pivoted between the cheeks of the bracket 40 and has an end 46 engaging rolls 47 and 48 in a slot in the ram 41. This lever is also provided with a cam portion 49 adapted to engage a roll 50 in the slotted end of the pin 43, and a further connection between the lever 45 and the pin 43 is made by a small cross pin engaging a cam slot 51 in the lever. The lever 45 has a forked end coöperating with a roll on the end of a lever 52 rigidly connected to an operating rock shaft 53 mounted on the base 10. This shaft extends across the machine and has its ends formed to receive an operating handle 54, whereby the handle may be placed on either the right or left side of the machine. The shaft 53 is normally held in a position with the arm 52 in engagement with a stop 55 by a spring 56 connected at one end to the lever 52 and at its other end to a pin 57 on the base 10. The lug 29 has mounted thereon a dial plate 58 which is provided with the usual characters corresponding to the characters on the stencil punches and dies mounted on the punch and die carrier. A stationary pointer 59 on the bracket 40 coöperates with the dial plate and positions the punches and dies at the cutting point as hereinafter described. A skeleton stripper 60 is mounted on the bracket 40 integral with pointer 59.

55 The base plate 10 has rotatively mounted therein a shaft 65 which is adapted to receive and support the blank carriage. This blank carriage is shown in detail in Figs. 4 and 9 and comprises a hub 66 having formed thereon thin radially extending arms 67 and provided with a rim 68 to form a spider. The blank holding means comprises a pair of upper flaring rims 69 and 70 and a lower flaring rim 71 connected by vertical narrow strips 72. These strips 72 are preferably in-

tegral with the upper rims and are secured to the lower rim in any desired manner, as by electro-welding. The rims 69, 70 and 71 and the connecting strips will thus form a cylindrical element of skeleton construction, 70 and this element is secured to the rim 68 in any desired manner as by screws or by electro-welding, the skeleton element being preferably so positioned on the spider that the strips 72 will come opposite the arms 67. 75 The hub 66 is splined on the shaft 65 by a key 73 in the shaft engaging a keyway in the hub, whereby the carriage will move with the shaft but is prevented from rotating with respect thereto. The stencil blank 80 can be inserted between the rims 69, 70 and 71 and the strips 72 and will thus be positioned in cylindrical form in the recess 14. The frictional clamping action of the skeleton element will ordinarily be sufficient to 85 hold the blank in position in the carriage, but the rims 69 and 70 may be provided with alined holes 74 adapted to receive a pin, which pin may be passed through the blank to hold it against movement in the carriage. 90 The flared construction of the rims permits easy insertion of the blank.

The means for rotating the blank carriage step by step will now be described. Referring to Figs. 3, 5 and 6, 75 designates a collar on the shaft 65 forming a thrust bearing for the shaft, and this shaft is further secured against endwise movement by means of a washer 76 and lock nuts 77. The lower end of the shaft has mounted thereon a ratchet 78 which is clamped in position by means of a nut 79. A pawl 80 sliding in a horizontal guideway 81 formed in a lug 82 on the base 10 has a connection with an arm 83 on the rock shaft 53. The pawl is jointed as shown at 84, and a spring 85 normally tends to move the pawl toward the ratchet. The pawl is provided with cam faces 86 and 87 adapted to be engaged by pins 88 and 89 respectively, extending downwardly from the base. The parts are so constructed that when the rock shaft 53 is in its normal position the pawl will be held out of engagement with the ratchet by the pin 88, and when the rock shaft is in its other extreme position the pawl will again be held out of engagement with the ratchet by the pin 89. During the first part of the movement of the rock shaft 53 the pawl will move into engagement with the ratchet and rotate the carrier one step, and this pawl will be moved out of engagement during the last part of the movement of the rock shaft. 110

The means for moving the carriage vertically step by step will now be described. Referring to Figs. 3, 7 and 8, 90 designates a lug preferably made integral with the base and bored to provide a bearing for a sliding shaft 91. This shaft has a laterally extending arm 92 which has pivoted thereon a 125

pawl 93 adapted to engage a series of spaced circumferential grooves 94 in the hub 66. The shaft 91 is connected by a link 95 with an arm 96 rigidly connected with an operating rock shaft 97. This rock shaft extends across the machine and has both ends thereof formed to receive an operating handle 98, whereby the handle may be placed on either the right or left hand side of the machine. A spring 99 normally holds the shaft 91 and its pawl at its lower limit, the downward movement being limited by a stop 100 engaging the upper face of the lug 90. The pawl 93 is moved into engagement with the grooves by means of a spring 101, while a strip 102 on the lug 90 has its upper end rounded to engage the end of the pawl so as to hold it out of engagement with the hub 66 when the shaft 91 is at its lower limit. The upper movement of the shaft and pawl are limited by the engagement of a cross pin 103 with the bottom face 104 of the lug 90. In order to latch the carrier in different adjusted positions, the shaft 95 is provided with a series of depressions 105 adapted to coöperate with a ball 106 on the hub 66, which ball is moved into the depressions by means of a spring 107 bearing at one end against the ball and at the other end against a plug 108 screwed into the hub. By means of this construction the carrier can be moved vertically step by step and will be latched in position. When the handle 98 is in normal position, the pawl 93 will be held out of engagement with the hub 66 so that the carrier may be freely moved vertically in either direction at this time. The carriage is provided with a hand wheel 109 preferably cast integral therewith. The carriage is moved down to its lower limit by hand.

The punches and dies may be of the usual construction. The dies may consist of a series of punched plates, and the punches may also be formed by punching. In punches and dies it is necessary to provide for draft; the die apertures in the die plates are accordingly flared while the sides of the punches are inclined to provide this draft. This is ordinarily obtained by filing by hand, which however involves expensive manual operations. In accordance with this invention a new method is evolved for forming these punches and dies whereby the draft is formed in a simple and inexpensive manner.

Figs. 10 and 11, and 14 and 15 show punch and die plates of the usual form. These punch and die plates are formed either by forging or by punching, and the sides of the punch projection and the sides of the aperture in the die plate are straight. In accordance with this invention the punch and die plates are formed in any desired manner, but preferably by the usual punching

or forging operations. This will produce the plates as shown in Figs. 10 and 11, and 14 and 15. The punch and die plates are then bent to conform to the required circular form of the punch and die carrier. The final complete form of the plates is shown in Figs. 12 and 13, and 16 and 17. By bending the plates to this form the sides of the punch projection and the sides of the die aperture will be inclined and flared as shown, this will provide the necessary draft. The bending of the plates may be performed in any well known manner, as by a set of bending dies. By the use of this method a punch and die are produced which will have the necessary draft without requiring expensive manual filing operations. It will be understood that either the punch plates or the die plates or both may be flat as shown in Figs. 10, and 11, and 14 and 15. In such cases the draft is obtained in the usual way, i. e., by filing. Moreover the die may be of cylindrical form as shown and the draft may be obtained partially or wholly by filing or in any other suitable manner.

The operation of the machine will be as follows: A blank is inserted in the carriage and this blank will be held in cylindrical form in the space 14 between the punches and dies. The blank is moved down to its lowest position, and in such a position with respect to the cutting point opposite the pointer 59 where it is desired to start the upper line of the stencil. The punch and die carriage is now rotated to position a selected set of punches and dies at the cutting point as noted by the dial and pointer. The handle 54 is now moved downwardly (to the left Fig. 2). During the first part of the movement of the handle the pin 43 will enter the flared aperture 44 and aline the selected set of punches and dies with respect to the cutting point. During this first movement the pawl 80 will also move into engagement with the ratchet 78 and move the blank carriage laterally one space. The arrangement of elements of the mechanism is such that the blank carriage will be fed one space and the pawl 80 will be again disengaged from the ratchet before the punch reaches the blank, whereby the blank carriage and the blank thereon will be stationary when the punch and die coöperate to cut the blank during the latter part of the movement of the handle 54. If the handle 54 is now released the parts will be returned to retracted position with the punch and the ram retracted and with the pawl in retracted position out of engagement with the ratchet as shown in Figs. 3 and 5. Another selected set of punches and dies is now positioned at the cutting point and the handle 54 is again operated. During the operation of the handle the blank carriage will be moved circumferentially to space the blank with respect to

90
95
100
105
110
115
120
125
130

the cutting point so as to space the next stencil character, and this next stencil character will be cut as before. In this way the successive stencil characters can be cut, the blank carriage being moved step by step to space the stencil characters in a stencil line. In order to move the blank to space the next stencil line, the handle 98 is moved downwardly (to the left Fig. 2) so as to cause the pawl 93 to engage one of the grooves 94 and move the carriage vertically on the shaft one space. When the handle is released the pawl will be returned to original position out of engagement with the hub 66 as shown in Figs. 3 and 7, the carriage being retained in adjusted position by means of the ball latch 106.

The arms 67 and the strips 72 of the carrier are so positioned with respect to the teeth on the ratchet 78 that a strip 72 will never come to rest at the cutting point and opposite a punch and die when the portion of the blank to be cut is positioned at the cutting point opposite the pointer 59 and the ram 41. These strips will therefore not interfere with the free operation of the punches. Furthermore the arms 67 will never come to rest at the cutting point, so that these arms being thin will not obstruct the view of the blank at the cutting point.

In the operation of the machine, the operator will stand over the machine opposite the cutting point, *i. e.*, to the left Figs. 1, 2 and 3. By referring to Fig. 3, it will be noted that the upper edge of the punch carrier 12 terminates at the upper edge of the punches and below the upper edge of the die carrier 11. The punch carrier and the punches thereon are also spaced a sufficient distance from the die carrier and the dies thereon, and the blank carrier positions the blank close to the die and a sufficient distance from the punch carrier and its punches, so that neither the punch carrier or its punches will obstruct the view of the blank at the cutting point if the eye is positioned above and to the left of the machine, Fig. 3. This will give the operator a clear view of the blank, more especially at the cutting point. This view is permitted in view of the fact that the punches and dies are so arranged as to expose the blank at the cutting point, and in view of the fact that the blank is arranged at an angle to the horizontal, instead of in horizontal planes. The skeleton construction of the carriage exposes substantially the entire blank, and the supporting strips come at such points that they never come opposite the blank at the cutting point. Moreover in view of the fact that the carriage is moved vertically to space the stencil lines, the cut stencil line will be raised above the punch and die carrier, so that it will be in plain view. It will be noted that the blank is supported at its

bottom or below the punches and dies, or generally speaking, inwardly of punches and dies. As will be seen from an inspection of Fig. 2, the punches and dies are in an upright and positive position, as viewed by the operator when in position to operate the machine. The cut stencil characters will, therefore, also be in an upright and positive position to the operator. The operator will, therefore, see a completed line in its positive position, and in view of this arrangement of parts permitting such an arrangement of the punches and dies, and in view of the fact that the operating mechanism, etc., is placed in such a position as to permit the operator to normally position his eye in such a position as to see the cut stencil line positively, the cut stencil line can be moved out of and above the carrier when cut so as to expose the lines successively to the full view of the operator. Since the cut line is visible as soon as cut, and as soon as the blank is spaced for the next line, the operator can readily position the second line with respect to the first line, etc. The machine is therefore entirely visible so that it is not necessary to feed the blank back out of the machine to expose the part having the stencil cut therein to view each time that such a view is desired.

Referring now to Figs. 20 to 28 inclusive, 110 designates a pair of end frames which support the punch and die carriers 111. This punch and die carrier is of substantially U shaped section as shown in Fig. 23 and is open at both ends so as to provide a vertical space for receiving the blank. The carrier has lugs 112 pivoted to the end frames 110 by means of bolts 113, and has slotted lugs 114 connected by bolts 115 to the end frames. The bolts 115 engage the slots 116 in the lugs 114, whereby the carrier 111 may be tilted and set at any suitable angle with respect to the horizontal, the carrier being clamped in adjusted position by means of the bolts 115.

The carrier 111 has mounted thereon a series of die plates 117, and this carrier is apertured as shown at 118 to permit the punchings to be discarded. The carrier is slotted longitudinally as shown at 119 so as to provide a slot extending along substantially the entire length of the carrier to receive the blank feeding and holding means as hereinafter described. The carrier is braced on each side of the slot 119 by horizontal flanges 120 and 121. A series of punch plungers 122 are mounted to slide in flanges 123 and 124 in the carrier, and each of these plungers is provided with a punch 125 adapted to coöperate with a die plate 117. Each plunger is provided with a spring 126 bearing at one end against the flange 123 and at its other end against the collar 127 secured to the plunger. The

springs are omitted in Fig. 20 for the sake of clearness. This collar may be provided with any suitable means for alining the punch with the die, as by flattening its 5 lower edge so as to bear against the upper face of the web 128. The carrier is also provided with a slot 129 extending therewith so as to receive the blank feeding mechanism hereinafter to be described. The 10 carrier is ribbed as shown in Figs. 21 and 23 so as to obtain a rigid construction.

A blank carriage 135 of substantially U shaped construction is adapted to move along the carrier 111, and is supported 15 thereon by rolls 136 and 137 engaging tracks 138 and 139 respectively, on the carrier 111. This carrier supports the mechanism for actuating the punches and for holding and feeding the blank. An operating plunger or 20 ram 140 is mounted to slide in the carrier and is provided with a hooked end 141 adapted to engage corresponding hooked ends on the punch plungers 123. A pin 142 on the ram 140 is adapted to coöperate with 25 inclined slots 143 of a plate 144 mounted on the web 124 of the punch and die carrier so as to aline the carrier with respect to a selected set of punches and dies. This plate is provided with the usual characters so as to 30 form a dial plate. An operating lever 145 is pivoted at 146 between a pair of lugs 147 on the carriage and has a handle 148. This lever is provided with a cam rib 149 embraced by cam rolls 150 on the ram 140. 35 Depression of the handle 148 will operate to move the ram inwardly and thereby cause a selected set of punches and dies to coöperate with the blank. The lever may be returned by a spring 151, or it may be returned manually. 40

The blank 154 is supported in the recess in the punch and die carrier by means of a blank carriage comprising a flared holder or trough 155 extending along the carrier and 45 supported at its ends by bars 156 mounted to slide vertically in guideways in the ends of the carrier 111. This carriage is maintained in any desired adjusted position in any suitable manner as by means of ball 50 latches as shown in Fig. 8.

The carriage 135 has bolted thereon or cast integral therewith a lug or projection 153 adapted to enter and project through the slot 129 in the punch and die carrier. 55 This lug 153 carries a stripper 157 and a feeding wheel 158 which is rotatively mounted in the lug and frictionally retained in position by means of a friction washer 159. This feeding roll has secured thereto or formed integral therewith a ratchet 160 with which coöperates a pawl 161 on a bar 162 slidably mounted in a bearing 163 in the carriage 135. The bar 162 has a pair of cam rolls 164 engaging a cam rib 165 on the lever 145. A smooth

pressure wheel or roll 166 is mounted rotatively on a plate 167, which is in turn slidably mounted on a shelf 168 formed on the carriage 135. The plate 167 is retained in position by means of gibbs 169, and is normally moved toward the feeding wheel 158 by means of springs 170 mounted in the recesses 171 in the plate 167 and bearing at one of their ends against the plate and at their other ends against lugs 172 projecting upwardly from the shelf 168 into recesses 171. A block 173 is loosely mounted on the plate 167 and this block has a straight blank engaging edge positioned opposite a plate 174 on the lug 153. The plate 174 has a sharp 70 straight edge engaging the blank so that this edge will sink a slight distance into the blank when this blank is pressed thereagainst by the block 173. The plate is held in adjusted position by screws working in 75 slots on the lug 153 as shown in Fig. 25.

When the handle 148 is moved downwardly the cam 165 will operate to move the bar 162 inwardly and thereby cause the pawl 161 to move the ratchet 160 so as to move the wheel 158 one space. The cams 149 and 165 are so relatively positioned with respect to their cam rolls, and the cam 165 is so formed that the pawl will be operated to space the blank during the first movement of the operating lever 145. The cam rolls 164 will reach the straight part of the cam 165 before the punch reaches the blank, so that the blank will be fed and will again be at rest when the punch and die coöperate to cut the 100 blank.

The carriage 111 has projecting therefrom a pair of lugs 180 which have rotatively mounted therein square shafts 181 and 182. The shaft 181 has rigidly connected thereto 105 at each end an arm 179, and each arm has pivoted thereon pawls 183 and 184 adapted to coöperate with notches 185 in the bars 156. The shaft 182 has rigidly connected thereto at each end a double armed lever, 110 each arm 186 of which is connected by links 187 and 188 with the pawls 183 and 184 respectively. The pawls are normally moved toward the bars 156 by means of springs as shown in Fig. 23, and the connections between the links 187 and 188 and the arms 115 186 are pin and slot connections as shown in Fig. 23.

Referring now to Figs. 23, 27 and 28, 139 and 190 designate a pair of arms or hand levers mounted on and movable with the carriage and having square holes receiving the shafts 181 and 182. The arms are provided with shouldered collars or hubs 192 and 193 taking into similarly shaped recesses in a 125 lug 191 on the carriage. In order that these hubs may be placed in position the lug 191 is split and provided with a removable cap which may be clamped in position on the lug. This cap may be so proportioned that 130

it will frictionally clamp hubs and frictionally retain the arms in position, but this cap may be provided with a pin 195 having a rounded end adapted to engage the arm 190 so as to hold it in adjusted position.

When the arm 190 is in the position shown in the drawings the pawls 184 will be held out of contact with the bars 156 while the pawls 183 are permitted to move into engagement with these bars. If the arm 189 be now depressed the pawl 183 will engage the notches 185 in the bars 156 and move the blank carriage vertically. By oscillating the arm 189 the blank carriage will be raised step by step so as to feed the blank vertically. The blank carriage may be held in adjusted position by means of suitable latching means as hereinbefore described. In order to lower the blank carriage the arm 190 is moved downwardly until its upper edge snaps over the pin 195, which will operate to move the pawls 183 out of engagement and throw the pawls 184 into engagement with the bars 156. Oscillation of the arm 189 will now operate to move the blank carriage downwardly step by step. It will be understood that a spring may be provided to hold the arm 189 in normal position, but the arms 189 and 190 may be held in position frictionally as hereinbefore described.

At the time when the blank carriage is to be moved vertically the feeding mechanism must be placed in such a position as to release the blank. This construction will now be described. The arm 189 has projecting therefrom an arm 196 which connects by a link 197 with a bar 198 sliding vertically in bearings 199 and 200 on the carriage 135. The upper end 201 of this bar co-operates with a flared hole 202 in the plate 167, and a laterally extending branch 203, connected to the arm 198 at 204, co-operates with a like flared hole 205 in the plate. When the arm 189 is moved downwardly to raise the blank carriage the ends 201 and 203 in the bar 198 will during the first part of the movement of the arm be raised to engage the flared holes 202 and 205 and move the plate 167 against the tension of its springs 170, so as to move the wheel 166 and the block 173 out of engagement with the blank, thereby freeing the blank and permitting it to be fed vertically by the vertical movement of the blank carriage. The pawls 183 and the arm 179 are preferably so positioned with respect to the arm 196 that the pawls 183 will be out of engagement with the notches 185 when the ends 201 and 203 are out of engagement with the holes 202 and 205, whereby the plate 167 will be retracted before the pawls 183 engage the notches 185. When the carriage is to be fed downwardly the blank is usually not in the machine. In view of the fact however that the feeding takes place while the arm 179 moves downwardly, the

blank will be disengaged by the wheel 166 and the block 173 during the greater part of this downward movement.

It is sometimes desirable to throw the block 173 out of action without throwing the feeding wheel 166 out of action. This is accomplished as follows: Referring to Figs. 25 and 26, 206 designates an eccentric pin threaded into the end 201 of the bar 198 and having handle projections 207. When the pin is in the position shown in Figs. 25 and 26 it is held entirely out of engagement with the edge of the hole 202; when however it is moved through 180° it will operate to engage the plate and swing this plate 167 on the lug 172 so as to throw the block 173 out of engagement with the blank leaving the wheel 166 in engagement. The construction may be such that the rotation of the pin 206 will cause the pin to clamp the end 201 and thus lock it in position.

The operation of the machine will be obvious. The blank is inserted in its carriage by slightly separating the wheel and the block 173 from the wheel 158 and the plate 174. This blank is then so positioned with respect to the cutting point, which cutting point is on a line with the feeding rolls, where it is desired to start the upper line of the stencil. The carriage 135 is now moved so as to position it with respect to a selected set of punches and dies. The operating handle 148 is now moved downwardly, and during this downward movement the blank will first be fed transversely one space and thereafter the punch and die will co-operate to cut the blank. The handle is now returned to original position and the carrier is moved to position another selected set of punches and dies at the cutting point. If the handle is now again operated the blank will be spaced during the first part of the movement of the handle and thereafter the punch and die will co-operate to cut the blank. The vertical spacing is obtained by the operation of the arm or handle 189 as described heretofore.

It will be noted that the end of the plate 174 is beveled to form a comparatively sharp straight edge. This plate will therefore sink slightly into the blank. It will be noted also that the sunken line will be on a line with the wheels 158 and 166, and if the feed is in the direction of the arrow Fig. 25 the rolls will pull the blank between the two members 173 and 174 clamping the blank. In view of the fact that the edge of the plate 174 sinks into the blank, and in view of the fact that this sunk portion extends for some distance along the blank, the tendency is to feed the blank in a straight line as determined by the direction of the straight edge of the plate 174. By means of this construction a very accurate feed is obtained along a straight line.

The axes of the feed wheels lie on a line which is always positioned along a selected set of punches and dies when positioned at the cutting point. The blank is therefore 5 always supported at the cutting point.

In this construction, as in the construction shown in Figs. 1 to 28 inclusive, the blank is supported at an angle to the horizontal, and the parts are so constructed and 10 arranged as to expose the blank at the cutting point and on either side. The feed wheels being placed below the punches and dies will not obstruct the blank. The work 15 of the machine is therefore visible. The blank carriage is ribbed for strength, for it will be noted that this carriage takes all the strain during the punching operation. The carrier 111 may be tilted at any suitable angle with respect to the horizontal to 20 suit the operator.

It is sometimes desirable to cut a circular stencil, that is, a stencil having the stencil characters arranged circularly thereon with respect to a common center. Means for cutting such stencils are shown in Figs. 29 to 25 34 inclusive and these means are shown as attachments for the machines shown in Figs. 1 to 28 inclusive.

Referring first to Figs. 29 to 31 inclusive, 30 which show an attachment for the machine illustrated in Figs. 1 to 19. inclusive, 210 designates a bracket which may be removably bolted to the base 10 of the machine. This bracket extends upwardly for a considerable 35 distance above the blank carriage and is provided with a series of apertures 211 spaced apart a distance equal to the spaces between the stencil lines. A blank carrier comprising a collar 212 having a 40 screw threaded end 213 is adapted to be clamped on the collar by means of a threaded nut 214. A collar 215 has a reduced end 216 adapted to be placed in one of the apertures 211 and adapted to receive a threaded 45 stem 217 on the collar 212. The collar 215 carries a ratchet 218 and a knurled head 219. The collar 212 carrying the blank, and the collar 215 carrying the ratchet, are adapted to be connected by the stem 217 so 50 as to revolve as a unit in the bracket 210, and a friction washer 220 is interposed between the collar 212 and the bracket 210 so as to frictionally retard the movement of the connected parts of the blank carrier. 55 The bracket 210 has pivoted thereon a bell crank lever 221, one end of which has connected thereto a link 222 which passes through the base 10 and connects with an arm 223 on the rock shaft 53. The other 60 arm of the bell crank lever is connected with a bar or rod 224 sliding in a bearing 225 on the bracket 210. This bar 224 has pivoted thereto a pawl lever 226 guided by and sliding in a slideway 227 in a lug 233 on the bracket 210. The pawl 226 has teeth 228,

229, 230 and 231 thereon, the teeth being positioned in groups of 1, 2, 2 and 4 teeth respectively, as shown in Fig. 30. The pawl 226 is moved toward the ratchet 218 by a spring 232. When the hand lever 54 is operated to rock the shaft 53, the pawl 226 will be reciprocated vertically. During this vertical reciprocation the teeth on the pawl will engage the ratchet to move it step by step. The teeth on the pawl are so constructed and arranged that when the blank is in its lowest position, that is, when the blank carrier is supported in the lower hole 211, so as to cut the upper line, the angular movement given to the blank will be a maximum, while when the blank is in a position with its carrier engaging the uppermost hole 211 the angular movement given to the blank will be a minimum. This is required in order that the spacing of the stencil characters may be uniform. If the hand lever 54 is oscillated the blank carrier as well as the blank carriage will be moved step by step so as to feed the blank, since both the blank carrier and the blank carriage are operated by the same lever and are moved in the same direction. It will be noted that the blank carrier may be freely revolved at all time.

Referring now to Figs. 32 to 34 inclusive, 95 which show a circular stencil cutting attachment for the machine shown in Figs. 20 to 28 inclusive, 240 designates a bracket which is removably clamped on the carriage 135 by means of bolts 241. The bracket is 100 provided with a series of apertures 242 adapted to receive the threaded stem 243 of a blank carrier 244, the blank being clamped to the carrier by means of a nut 245. When it is desired to cut a circular stencil 105 the attachment is bolted to the carriage 235 and the eccentric pin 206 (Figs. 25 and 26) is moved to a position to throw the block 173 out of engagement with the blank. To 110 cut the first stencil, the stem 243 of the carrier is passed through the lowermost hole 242 and secured in position. If the machine is now operated the blank will be fed by the feeding wheels 158 and 166 around the stem 243 as an axis so as to cut a circular 115 stencil. The successive lines may be cut by successively placing the stem 243 in the different holes vertically of the bracket 240. In this case the blank can be fed by the feeding rolls and the spacing will of course 120 be uniform.

It will therefore be seen that the invention 125 accomplishes its objects. A machine is produced in which the blank will be exposed at the cutting point whereby the work in the machine is visible. This is obtained by so constructing the parts that the blank will be positioned at an angle to the horizontal instead of in a horizontal plane. The blank need not necessarily be positioned at a right 130

angle to the horizontal but this angle may be at a more acute or obtuse inclination from the standpoint of the operator. Thus in the construction shown in Figs. 20 to 28 inclusive the punch and die carrier is swiveled so that it may be adjusted in different angular positions with respect to the horizontal. Moreover in the construction shown in Figs. 1 to 19 inclusive the blank 10 may also be positioned at a more acute or obtuse angle to the horizontal than that shown. This can be accomplished in various manners, as for instance by inclining the base and axis of rotation of the carrier and carriage.

It is further obvious that various changes may be made in the details of this construction without departing from this invention, and it is therefore to be understood that this 20 invention is not to be limited to the specific construction shown and described.

Having thus described the invention what is claimed is:

1. A stencil cutting machine comprising 25 a blank carrier, a punch and die carrier, and a series of cutting punches and dies arranged in definite relation on said punch and die carrier to form sets adapted to cut stencil characters in a blank positioned by 30 said blank carrier between said punches and dies, said carriers being relatively movable to position a selected set of punches and dies at the cutting point, said carriers being constructed and relatively arranged to space the 35 blank a sufficient distance from the stencil cutting elements on one side of the blank, and said punch and die carrier terminating on said side of the blank in such a position, as to leave the blank unobstructed to view 40 at the cutting point between the punches and dies, whereby the work in the machine is visible.

2. A stencil machine comprising blank 45 supporting and feeding means, a punch and die carrier, and a series of cutting punches and dies arranged in definite relation on said carrier to form sets adapted to cut stencil characters in a blank positioned by said blank supporting and feeding means between 50 said punches and dies, said carrier being movable relatively with respect to the blank to position a selected set of punches and dies at the cutting point, said blank supporting and feeding means and said carrier and the 55 punches and dies thereon, being constructed and relatively arranged to space the blank a sufficient distance from the stencil cutting elements on one side of the blank, and said carrier terminating on said side of the blank, 60 in such a position, as to leave the blank unobstructed to view at the cutting point between the punches and dies, whereby the work in the machine is visible.

3. A stencil cutting machine comprising a blank carrier constructed and arranged

to position a blank at an angle to the horizontal, a punch and die carrier, and a series of cutting punches and dies arranged in definite relation on said punch and die carrier, and at an angle to the vertical, to form sets 70 adapted to cut stencil characters in the blank positioned by said blank carrier between said punches and dies, said carriers being relatively movable to position a selected set of punches and dies at the cutting point, said carriers being constructed and relatively arranged to space a blank a sufficient distance 75 from the stencil cutting elements on one side of the blank and to position said parts relatively, so as to leave the blank unobstructed 80 to view at the cutting point between the punches and dies, whereby the work in the machine is visible.

4. A stencil cutting machine comprising a carrier, a series of punches and dies arranged in definite relation on said carrier to 85 form sets adapted to cut stencil characters in a blank positioned at an angle to the horizontal between said punches and dies, and blank supporting and feeding means 90 adapted to position the blank between said punches and dies, said punches and dies being movable relatively with respect to the blank to position a selected set of punches and dies at the cutting point, said blank supporting and feeding means being constructed 95 and arranged to expose the blank at the cutting point, a part of said carrier and the cutting elements on one side of the blank being spaced from the blank, and said part 100 terminating in such a position so as to leave the blank unobstructed to view at the cutting point between the punches and dies, whereby the work of the machine is visible.

5. A stencil cutting machine comprising a carrier, a series of punches and dies arranged in definite relation on said carrier to 105 form sets adapted to cut stencil characters in a blank positioned at an angle to the horizontal between said punches and dies, means 110 for feeding the blank laterally to space the stencil characters, and vertically to space the stencil lines, adapted to position the blank between said punches and dies, said punches and dies being movable relatively with respect to the blank to position a selected set 115 of punches and dies at the cutting point, said blank supporting and feeding means being constructed and arranged to expose the blank at the cutting point, a part of said carrier and the cutting elements on one side of the blank being spaced from the blank, and said part terminating in such a position 120 so as to leave the blank unobstructed to view at the cutting point between the punches and dies, whereby the work in the machine is visible.

6. A stencil cutting machine comprising a carrier, a series of punches and dies arranged in definite relation on said carrier to 130

- form sets adapted to cut stencil characters in a blank positioned at an angle to the horizontal between said punches and dies, a blank carrier positioned between said punches and dies for supporting said blank between said punches and dies and constructed to expose the blank at the cutting point, said punches and dies being movable relatively with respect to the blank to position a selected set of punches and dies at the cutting point, a part of said punch and die carrier and the stencil cutting elements on one side of the blank being spaced from the blank and constructed and arranged so as to leave the blank unobstructed to view at the cutting point between the punches and dies, whereby the work in the machine is visible, and means for feeding said blank carrier step by step.
- 20 7. A stencil cutting machine comprising a carrier, a series of punches and dies arranged in definite relation on said carrier to form sets adapted to cut stencil characters in a blank positioned at an angle to the horizontal between said punches and dies, a blank carrier of skeleton construction positioned between said punches and dies for supporting said blanks between said punches and dies and constructed to expose the blank at the cutting point, said punches and dies being movable relatively with respect to the blank to position a selected set of punches and dies at the cutting point, a part of said punch and die carrier and the stencil cutting elements on one side of the blank being spaced from the blank and constructed and arranged so as to leave the blank unobstructed to view at the cutting point between the punches and dies, whereby the work in the machine is visible, and means for feeding said blank carrier step by step.
- 25 8. In a stencil cutting machine, the combination with a series of stencil cutting punches and dies arranged in definite relation to form sets adapted to cut stencil characters in a blank positioned at an angle to the horizontal, of a blank feeding carriage of skeleton construction positioned between said punches and dies, and constructed to leave the blank exposed to view.
- 30 9. In a stencil cutting machine, the combination with a series of stencil cutting punches and dies arranged in definite relation to form sets adapted to cut stencil characters in a blank positioned at an angle to the horizontal, of a blank feeding carriage of skeleton construction positioned between said punches and dies, and means for moving said carriage vertically.
- 35 10. In a stencil cutting machine, the combination with a punch and die carrier, of a series of stencil cutting punches and dies arranged in definite relation in sets radially on said carrier and movable relatively radi-
- 40 ally of said carrier to cut stencil characters in a blank, and means for holding a blank in coöperative relation with respect to said punches and dies.
- 45 11. In a stencil cutting machine, the combination with a punch and die carrier, of a series of stencil cutting punches and dies arranged in definite relation in sets radially on said carrier and movable relatively radi-
- 50 ally of said carrier to cut stencil characters in a blank, and a blank carriage mounted to rotate relatively with respect to said punches and dies.
- 55 12. In a stencil cutting machine, the combination with a punch and die carrier, of a series of stencil cutting punches and dies arranged in definite relation in sets radially on said carrier and movable relatively radi-
- 60 ally of said carrier to cut stencil characters in a blank, a blank carriage, and means for feeding said carriage with respect to said punches and dies.
- 65 13. In a stencil cutting machine, the combination with a punch and die carrier, of a series of stencil cutting punches and dies arranged in definite relation in sets radially on said carrier and movable relatively radi-
- 70 ally of said carrier to cut stencil characters in a blank, a blank carriage, and means for feeding said carriage circumferentially with respect to said punches and dies.
- 75 14. In a stencil cutting machine, the combination with a punch and die carrier, of a series of stencil cutting punches and dies arranged in definite relation in sets radially on said carrier and movable relatively radi-
- 80 ally of said carrier to cut stencil characters in a blank, a blank carriage movable in rectangular paths transversely with respect to said punches and dies.
- 85 15. In a stencil cutting machine, the combination with a rotary carrier, of a series of stencil cutting punches and dies arranged in definite relation in sets on said carrier and adapted to cut stencil characters in a blank, and a rotatable blank carriage positioned between said punches and dies.
- 90 16. In a stencil cutting machine, the combination with a rotary carrier, of a series of stencil cutting punches and dies arranged in definite relation in sets on said carrier and adapted to cut stencil characters in a blank, and a rotatable and endwise movable blank carriage positioned between said punches and dies.
- 95 17. In a stencil cutting machine, the combination with a rotary carrier, of a series of stencil cutting punches and dies arranged in definite relation in sets on said carrier and adapted to cut stencil characters in a blank, a blank carriage positioned between said punches and dies, and means for rotating said carriage to feed the blank.
- 100 18. In a stencil cutting machine, the combination with a rotary carrier, of a series of stencil cutting punches and dies arranged

- in definite relation in sets on said carrier and adapted to cut stencil characters in a blank, a blank carriage positioned between said punches and dies, means for rotating 5 said carriage, and means for moving said carriage in a direction along its axis.
19. In a stencil cutting machine, the combination with a carrier, of a series of stencil cutting punches and dies arranged in definite relation in sets on said carrier, said carrier being rotatable to position said punches and dies at the cutting point, and a rotatable blank carriage positioned between said punches and dies and adapted to 10 position a blank with respect to said punches and dies.
20. In a stencil cutting machine, the combination with a carrier, of a series of stencil cutting punches and dies arranged in definite relation in sets on said carrier, said carrier being rotatable to position said punches and dies at the cutting point, and a rotatable blank carriage positioned between said punches and dies and adapted 15 to position a blank with respect to said punches and dies, and means for operating said punches and dies and for rotating said carriage to feed the blank.
21. In a stencil cutting machine, the combination with a carrier, of a series of punches and dies arranged in definite relation in sets radially on said carrier, and movable relatively radially to cut stencil characters in a blank, and a blank carriage 20 adapted to position a blank between said punches and dies.
22. In a stencil cutting machine, the combination with a carrier, of a series of punches and dies positioned radially on said carrier and movable relatively radially to coöperate with a blank, and a cylindrical blank carriage adapted to position a blank in cylindrical form between said punches and dies. 25
23. In a stencil cutting machine, the combination with a carrier, of a series of punches and dies positioned radially on said carrier and movable relatively radially to coöperate with a blank, said carrier being 30 rotatable to position the punches and dies at the cutting point, and a cylindrical blank carriage adapted to position a blank in cylindrical form between the punches and dies.
24. In a stencil cutting machine, the combination with a carrier, of a series of punches and dies positioned radially on said carrier and movable relatively radially to coöperate with a blank, said carrier being 35 rotatable to position the punches and dies at the cutting point, a cylindrical blank carriage adapted to position a blank in cylindrical form between the punches and dies, and means for rotating said carriage to feed the blank.
25. In a stencil cutting machine, the combination with a carrier, of a series of punches and dies positioned radially on said carrier and movable relatively radially to coöperate with a blank, said carrier being 40 rotatable to position the punches and dies at the cutting point, a cylindrical blank carriage adapted to position a blank in cylindrical form between the punches and dies, and means for operating said punches and dies and for moving said carriage endwise.
26. In a stencil cutting machine, the combination with a carrier, of a series of punches and dies positioned radially on said carrier and movable relatively radially to coöperate with a blank, said carrier being 45 rotatable to position the punches and dies at the cutting point, a cylindrical blank carriage adapted to position a blank in cylindrical form between the punches and dies, and means for rotating said carriage to space the stencil characters and for moving said carriage endwise to space the stencil lines. 50
27. In a stencil cutting machine, the combination with a carrier, of a series of punches and dies positioned radially on said carrier and movable relatively radially to coöperate with a blank, and a cylindrical blank carriage of skeleton construction adapted to position a blank in cylindrical 55 form between said punches and dies.
28. In a stencil cutting machine, the combination with a carrier, of a series of punches and dies positioned radially on said carrier and movable relatively radially to coöperate with a blank, said carrier being 60 rotatable to position the punches and dies at the cutting point, a cylindrical blank carriage adapted to position a blank in cylindrical form between the punches and dies, and means for operating said punches and dies and for moving said carriage. 100
29. In a stencil cutting machine, the combination with a carrier, of a series of punches and dies positioned radially on said carrier and movable relatively radially to coöperate with a blank, said carrier being 65 rotatable to position the punches and dies at the cutting point, a cylindrical blank carriage adapted to position a blank in cylindrical form between the punches and dies, means for operating said punches and dies and for rotating said carriage, and means for moving said carriage endwise. 110
30. In a stencil cutting machine, the combination with a carrier, of a series of stencil cutting punches and dies positioned radially on said carrier and movable relatively radially to coöperate with a blank, and a blank carriage adapted to position a blank between said punches and dies, said parts being 70 constructed and relatively arranged to space the part of the carrier on one side of the blank and the stencil cutting elements thereon from the blank, and position the 120

parts relatively to expose to view the portion of the blank having a stencil character cut therein.

31. In a stencil cutting machine, the combination with a carrier, of a series of stencil cutting punches and dies positioned radially on said carrier and movable relatively radially to coöperate with a blank, and a blank carriage adapted to position a blank between said punches and dies, said parts being constructed and relatively arranged to space the part of the carrier on one side of the blank and the stencil cutting elements thereon from the blank, and position the parts relatively to expose to view the portion of the blank having a line of stencil characters cut therein.

32. In a stencil cutting machine, the combination with a carrier, of a series of stencil cutting punches and dies positioned radially on said carrier and movable relatively radially to coöperate with a blank, a blank carriage adapted to position a blank between said punches and dies, and means for feeding said blank to space the stencil lines adapted to raise a cut stencil line above said carrier and expose it to view.

33. In a stencil cutting machine, the combination with a carrier, of a series of stencil cutting punches and dies positioned radially on said carrier and movable relatively radially to coöperate with a blank, and a blank carriage adapted to position a blank between said punches and dies, said carriage being movable to space a cut stencil line above said carrier and expose it to view.

34. In a stencil cutting machine, the combination with a carrier, of a series of punches and dies arranged in definite relation in sets horizontally on said carrier and movable relatively horizontally to cut stencil characters in a blank, a blank carriage adapted to position a blank between said punches and dies, and means for moving said punches and dies relatively to cut the blank.

35. In a stencil cutting machine, the combination with a carrier, of a series of punches and dies arranged in definite relation in sets horizontally on said carrier and movable relatively horizontally to cut stencil characters in a blank, a blank carriage adapted to position a blank vertically between said punches and dies, means for moving said punches and dies relatively to cut the blank, and means for moving said carriage to feed the blank.

36. In a stencil cutting machine, the combination with a carrier, of a series of stencil cutting punches and dies positioned horizontally on said carrier and movable relatively horizontally to cut stencil characters in a blank, a blank carriage adapted to position a blank vertically between said punches and dies, means adapted to coöperate with

any of said punches and dies for moving said punches and dies relatively to cut the blank, and means for feeding the blank to space the stencil characters and to space the stencil lines.

37. In a stencil cutting machine, the combination with a carrier, of a series of stencil cutting punches and dies positioned horizontally on said carrier and movable relatively horizontally to cut stencil characters in a blank, a blank carriage adapted to position a blank vertically between said punches and dies, and means adapted to coöperate with any of said punches and dies for moving said punches and dies relatively to cut the blank, said parts being constructed and relatively arranged to space the blank from a part of the carrier on one side of the blank and from the stencil cutting elements thereon, so as to expose to view the blank at the cutting point.

38. In a stencil cutting machine, the combination with a carrier, of a series of punches and dies arranged in definite relation in sets horizontally on said carrier and movable relatively horizontally to cut stencil characters in a blank, a blank carriage adapted to position a blank vertically between said punches and dies, means adapted to coöperate with any of said punches and dies for moving said punches and dies relatively to cut the blank, and means for moving the blank constructed to raise the cut stencil character above the part of the carrier on one side of the blank to expose the same to view.

39. In a stencil cutting machine, the combination with a carrier, of a series of punches and dies arranged in definite relation in sets horizontally on said carrier and movable relatively horizontally to cut stencil characters in a blank, a blank carriage adapted to position a blank between said punches and dies, means adapted to coöperate with any of said punches and dies for moving said punches and dies relatively to cut the blank, and means for moving the blank vertically constructed to raise the cut stencil line above the part of the carrier on one side of the blank to expose the same to view.

40. In a stencil cutting machine, the combination with a carrier, of a series of punches and dies arranged in definite relation in sets horizontally on said carrier and movable relatively horizontally to cut stencil characters in a blank, a blank carriage positioned vertically between said punches and dies, means adapted to coöperate with any of said punches and dies for moving said punches and dies relatively to cut the blank, and means for moving the blank vertically, constructed to raise the cut stencil above the part of the carrier on one side of the blank to expose the same to view.

41. In a stencil cutting machine, the com-

bination with a carrier, of a series of punches and dies arranged in definite relation in sets positioned horizontally on said carrier and movable relatively horizontally to cut stencil characters in a blank, a blank carriage adapted to position a blank vertically between said punches and dies, means adapted to coöperate with any of said punches and dies for moving said punches and dies relatively to cut the blank, means for moving the blank horizontally to space the stencil characters, and means for moving the blank vertically to space the stencil lines, constructed to raise the cut stencil above the part of the carrier on one side of the blank to expose the same to view.

42. In a stencil cutting machine, the combination with a carrier, of a series of punches and dies arranged in definite relation in sets horizontally on said carrier and movable relatively horizontally to cut stencil characters in a blank, a blank carriage positioned vertically between said punches and dies, and means adapted to coöperate with any of said punches and dies for moving said punches and dies relatively to cut the blank, said carriage being movable in reverse directions.

43. In a stencil cutting machine, the combination with a carrier, of a series of punches and dies arranged in definite relation in sets horizontally on said carrier and movable relatively horizontally to cut stencil characters in a blank, a blank carriage positioned vertically between said punches and dies, and means adapted to coöperate with any of said punches and dies for moving said punches and dies relatively to cut the blank, said carriage being movable vertically in reverse directions.

44. In a stencil cutting machine, the combination with a carrier, of a series of punches and dies arranged in definite relation in sets horizontally on said carrier and movable relatively horizontally to cut stencil characters in a blank, a blank carriage positioned vertically between said punches and dies, and means adapted to coöperate with any of said punches and dies for moving said punches and dies relatively to cut the blank, said carriage being movable vertically and horizontally in reverse directions.

45. In a stencil cutting machine, the combination with a carrier having a series of co-operating stencil cutting punches and dies thereon, of a cylindrical blank carriage adapted to hold and position a blank in cylindrical form between said punches and dies.

46. In a stencil cutting machine, the combination with a carrier having a series of co-operating stencil cutting punches and dies thereon, of a cylindrical blank carriage adapted to hold and position a blank in cylindrical form between said punches and

dies, and a center support for said carriage having arms extending over said carrier.

47. In a stencil cutting machine, a cylindrical blank carriage, and means on said carriage adapted to hold and support a blank in cylindrical form, said parts being constructed and arranged to leave both sides of the blank free for operation of the stencil cutting punches and dies.

48. In a stencil cutting machine, a blank carriage comprising a cylindrical skeleton structure, and means on said carriage, adapted to support and hold a blank in cylindrical form, said parts being constructed and arranged to leave both sides of the blank free for operation of the stencil cutting punches and dies.

49. In a stencil cutting machine, a blank carriage comprising a cylindrical skeleton structure adapted to support a blank in cylindrical form, and a center hub therefor, said parts being constructed and arranged to leave both sides of the blank free for operation of the stencil cutting punches and dies.

50. In a stencil cutting machine, a blank carriage comprising a cylindrical skeleton body adapted to support a blank in cylindrical form, a hub, and arms connecting said hub and said body, said parts being constructed and arranged to leave both sides of the blank free for operation of the stencil cutting punches and dies.

51. In a stencil cutting machine, a blank carriage comprising upper and lower rims, stays connecting said rims to form an open cylindrical frame adapted to support a blank in cylindrical form, and means for supporting said frame.

52. In a stencil cutting machine, a blank carriage comprising upper and lower flaring rims, stays connecting said rims to form an open cylindrical frame adapted to support a blank in cylindrical form, and means for supporting said frame.

53. In a stencil cutting machine, a blank carriage comprising an open cylindrical frame adapted to support a blank in cylindrical form, and means for rotatively supporting said carriage, said parts being constructed and arranged to leave both sides of the blank free for operation of the stencil cutting punches and dies.

54. In a stencil cutting machine, a blank carriage comprising an open cylindrical frame adapted to support a blank in cylindrical form, a hub for said frame, means for supporting said hub, and means for rotating said hub and for moving it endwise, said parts being constructed and arranged to leave both sides of the blank free for operation of the stencil cutting punches and dies.

55. In a stencil cutting machine, a blank carriage comprising an open cylindrical

frame adapted to support a blank in cylindrical form, a hub for said frame, a shaft for supporting said hub, means for sliding said hub on said shaft, and means for rotating said hub, said parts being constructed and arranged to leave both sides of the blank free for operation of the stencil cutting punches and dies.

56. In a stencil cutting machine, a movable blank carriage, and means for moving said carriage step by step, said moving means becoming disengaged from said carriage at the end of each step by step movement of the carriage to permit it to be moved freely in reverse directions.

57. In a stencil cutting machine, a movable blank carriage, and means for moving said carriage step by step in rectangular paths, said moving means becoming disengaged from said carriage at the end of each step by step movement of the carriage to permit it to be moved freely in reverse directions.

58. In a stencil cutting machine, a rotatable and endwise movable carriage, and means for moving said carriage rotatively and endwise step by step, said moving means becoming disengaged from said carriage at the end of each step by step movement of the carriage to permit it to be moved freely in reverse directions.

59. A stencil cutting machine comprising a carrier, a series of punches and dies arranged in definite relation on said carrier to form sets adapted to cut stencil characters in a blank positioned at an angle to the horizontal between said punches and dies, and blank supporting and feeding means adapted to position the blank between said punches and dies, said punches and dies being movable relatively with respect to the blank to position a selected set of punches and dies at the cutting point, said blank supporting and feeding means engaging the blank below said punches and dies, said blank supporting and feeding means being constructed and arranged to expose the blank at the cutting point, a part of said carrier and the cutting elements on one side 50 of the blank being spaced from the blank, and said part terminating in such a position as to leave the blank unobstructed to view at the cutting point between the punches and dies, whereby the work in the machine is visible.

60. A stencil cutting machine comprising a blank carrier, a punch and die carrier and a series of cutting punches and dies arranged in definite relation on said punch and die carrier to form sets adapted to cut stencil characters in a blank positioned by said blank carrier between said punches and dies, said carriers being relatively movable to position, a selected set of punches and dies at the cutting point, said carrier sup-

porting the blank inwardly of said punches and dies, said carriers being constructed and relatively arranged to space the blank a sufficient distance from the stencil cutting elements on one side of the blank, and said 70 punch and die carrier terminating on said side of the blank in such a position as to leave the blank unobstructed to view at the cutting point between the punches and dies, whereby the work in the machine is visible. 75

61. In a stencil cutting machine, the combination with stencil cutting mechanism, of a blank carrier, means for supporting said carrier for rotative movement, and feeding mechanism comprising a ratchet on said carrier and a pawl member having a plurality of sets of teeth engaging said ratchet.

62. A stencil cutting machine comprising a vertical carrier, a series of cutting punches and dies arranged in definite relation on 85 said carrier for relative horizontal movement thereon, to form sets adapted to cut stencil characters in a blank positioned between said punches and dies, said carrier being movable relatively with respect to the 90 blank to position a selected set of punches and dies at the cutting point, means for moving said punches and dies relatively, means for feeding the blank to space the stencil characters, and means for positioning the 95 blank in a plurality of vertical positions to space the stencil lines, said parts being constructed and arranged to permit the blank to move upwardly and away from said carrier when spacing the stencil lines so as to 100 position the cut stencil line above said carrier, whereby the work in the machine is visible.

63. A stencil cutting machine comprising a vertical carrier, a series of cutting punches 105 and dies arranged in definite relation on said carrier, for relative horizontal movement thereon, to form sets adapted to cut stencil characters in a blank positioned between said punches and dies, said carrier 110 being movable relatively with respect to the blank to position a selected set of punches and dies at the cutting point, means for moving said punches and dies relatively, means positioned below said punches and 115 dies for feeding the blank to space the stencil characters, and means for positioning the blank in a plurality of vertical positions to space the stencil lines, said parts being constructed and arranged to permit the blank 120 to move upwardly and away from said carrier when spacing the stencil lines so as to position the cut stencil line above said carrier, whereby the work in the machine is visible. 125

64. A stencil cutting machine comprising a vertical carrier, a series of cutting punches and dies arranged in definite relation on said carrier for relative horizontal movement thereon, to form sets adapted to cut stencil 130

characters in a blank positioned between said punches and dies, said carrier being movable relatively with respect to the blank to position a selected set of punches and dies at the cutting point, means for moving said punches and dies relatively, means engaging and supporting the blank below said punches and dies for feeding the blank to space the stencil characters, and means for 5 positioning the blank in a plurality of vertical positions to space the stencil lines, said parts being constructed and arranged to permit the blank to move upwardly and away from said carrier when spacing the stencil lines so as to position the cut stencil line 10 above said carrier, whereby the work in the machine is visible.

65. A stencil cutting machine comprising a vertical carrier, a series of cutting punches 20 and dies arranged in definite relation on said carrier for relative horizontal movement thereon, to form sets adapted to cut stencil characters in a blank positioned between said punches and dies, said carrier being movable relatively with respect to the blank to position a selected set of punches and dies at the cutting point, means for moving said punches and dies relatively, means for feeding the blank to space the 25 stencil characters, and means for feeding the blank vertically upward to space the stencil lines, said parts being constructed and arranged to permit the blank to move upwardly and away from said carrier when 30 spacing the stencil lines so as to position the cut stencil line above said carrier, whereby the work in the machine is visible.

66. A stencil cutting machine comprising a vertical carrier, a series of cutting punches 40 and dies arranged in definite relation on said carrier for relative horizontal movement, to form sets adapted to cut stencil characters in a blank positioned between said punches and dies, said carrier being 45 movable relatively with respect to the blank to position a selected set of punches and dies

at the cutting point, means for moving said punches and dies relatively, means for feeding the blank to space the stencil characters, and means for positioning the blank in a 50 plurality of vertical positions to space the stencil lines, said parts being constructed and arranged to permit the blank to move upwardly and away from said carrier when spacing the stencil lines so as to position the cut stencil line above said carrier, said punches and dies being constructed to form 55 stencil characters positioned positively with respect to the operator when in a position for operating the machine, whereby the 60 work of the machine is visible.

67. A stencil cutting machine comprising a vertical carrier, a series of cutting punches and dies arranged in definite relation on said carrier for relative horizontal movement thereon, to form sets adapted to cut stencil characters in a blank positioned between said punches and dies, said carrier being movable relatively with respect to the blank to position a selected set of punches 70 and dies at the cutting point, means for moving said punches and dies relatively, means for feeding the blank to space the stencil characters, and means for positioning the blank in a plurality of vertical positions to space the stencil lines, said parts being constructed and arranged to permit the blank to move upwardly and away from said carrier when spacing the stencil lines so as to position the cut stencil line 75 above said carrier, said punches and dies being constructed to form stencil characters positioned positively and in an upright position with respect to the operator when in a position for operating the machine, whereby 80 the work in the machine is visible.

In testimony whereof I affix my signature in the presence of these two witnesses.

THEODÓRE BIRKENMAIER.
